UNITED STATES PATENT OFFICE.

FRANK WILLIAM MANTON AND JAMES NATHAN MANTON, OF TORONTO, ONTARIO,
CANADA.

PRINTER'S GALLEY.

Application filed July 25, 1921. Serial No. 487,469.

To all whom it may concern:

Be it known that we, FRANK WILLIAM MANTON and JAMES NATHAN MANTON, subjects of the King of Great Britain, and 5 residents of 105 Elizabeth Street, in the city of Toronto, county of York, Province of Ontario, Dominion of Canada, have invented certain new and useful Improvements in Printers' Galleys, of which the following is 10 a specification.

The invention relates to improvements in printers' galleys as described in the present specification and shown in the accompanying drawings that form a part of the same.

15 The invention consists essentially of the novel features of construction whereby the type is locked in predetermined position on the galley by means of one or more racks adapted to be secured to the walls of the galley and adjustable in relation to graduations 20 of measurement carried by said galley.

The objects of the invention are to provide a form of galley on which the type may 25 be properly measured and aligned and securely locked in position prior to transfer to the form, to reduce to a minimum the time required in type setting and generally to provide a printer's galley which will be inexpensive to construct, simple of adjustment and efficient.

30 In the drawings Figure 1 is a perspective view of the device, a portion of one of the side walls being broken away to disclose the method of securing the adjustable rack thereto.

Figure 2 is a side elevation of one of the racks, portions thereof being broken away to disclose the interior construction.

Figure 3 is a perspective view of the bar 40 adapted to interlock with the rack.

Figure 4 is a cross sectional view showing a modified means of constructing the side walls of the galley, said section being taken through a portion of galley and side wall 45 corresponding to the line A—A of Figure 1.

Like numerals of reference indicate corresponding parts in the various figures.

Referring to the drawings 1 represents the tray bottom which in practice may be of any 50 desired shape but which in the drawings is shown as being of rectangular shape in plan, said tray being provided with a comparatively shallow end wall 2 and opposing side walls 3 and 4, all of said walls preferably 55 being substantially square in cross section.

The top sides of the walls 2, 3 and 4 and the open end of the tray are provided with graduations 5 to correspond to the standard measurements in printing.

The inner faces of the walls 2, 3 and 4 are 60 provided with pin openings 6 spaced in accordance with the graduations 5.

7 is a rack slidable over the surface of the tray between the side walls 3 and 4, said rack being provided at one end with one or 65 more rigidly disposed dowel pins 8 adapted to be inserted in the desired opening or openings 6 and at its other end being provided with a bolt 9 slidably mounted in a longitudinal opening 10 in the rack, said 70 bolt having an enlarged body portion 11 disposed wholly within said opening and spring held normally to its outermost position by means of a spring 12 disposed between the inner end of said body and the end 75 of said opening.

13 is a lever extending through a slot 14 in the enlarged portion 15 of the rack 7 and pivoted as at 16 and having its lower end 17 extending through a slot 18 in the body 11, 80 said lever being for the purpose of operating the bolt 9.

The enlarged portion 15 of the rack 7 is preferably extended outwardly to project past the wall 3 in a finger 19 when the rack 85 is in position on the tray and the lever 13 is preferably turned outwardly parallel with said finger forming finger grips adapted to facilitate the adjusting of the rack.

The top side of the rack 7 is notched 90 transversely for the greater portion of its length forming slots 20.

21 is a bar of right angle cross section having a filling 22 at one end thereof from which projects a pin 23 and adapted to 95 be inserted in one of the openings 6 in the end wall 2, said bar terminating even with the open end of the tray and being adapted to be locked rigidly in position by inserting one of its sides in a slot 20.

The top side of the bar 21 is provided with graduations corresponding with the 100 graduations on the side walls 3 and 4.

In Figure 4 of the drawings a modified form of construction is shown in which the 105 walls of the tray are provided with metal linings 24 screwed or otherwise secured to said walls and provided with openings corresponding to the openings 6. This form of construction permits of the renewal of the 110

linings when the walls of the openings 6 have become worn.

In the use of this invention the amount of space to be occupied by the printing is first determined and a corresponding space on the galley is then measured off by placing the rack 7 the required distance from the end 2, the rack being secured by simply inserting the pin or pins 8 in the proper 10 openings 6 in the wall 4 and pressing the lever 13 downwardly to force the bolt inwardly to permit of the rack dropping past the wall 3 to its portion on the tray when the lever is then released permitting the bolt 15 to enter the opening 6 in the wall 3. The bar 21 is then placed the required distance from the side wall 4 and locked by inserting the pin 23 in the proper opening in the end wall 2 and the vertical wall in the corresponding slot 20 in the rack 7. The type 20 are then placed in the enclosure thus formed between the end wall 2, the side wall 4, the rack 7 and the bar 21, in proper position for transfer to the form.

25 What we claim is:—

A printer's galley comprising a tray having an end and side walls, said walls being provided with metal facings having

pin openings in the inner faces thereof, said walls also being graduated on the top sides 30 thereof, a rack having rigid projections from one end fitting openings in one of said walls, a bolt slideable in an opening in the other end of said rack and spring held to its extended position and adapted for insertion in an opening in the opposing side wall, said rack being enlarged above said bolt and projecting endwise in a finger adapted to extend over the corresponding side wall, said lever being pivoted in a slot 40 in said enlarged portion and having its lower end extending into a slot in said bolt, said rack being notched transversely along its top side, and a bar, right angle in cross section, and having one of its sides adapted 45 for insertion in one or other of said notches and having a rigid projection from one end fitting an opening in said end wall.

Signed at the city of Toronto, Province of Ontario, this 29th day of June 1921.

FRANK WILLIAM MANTON.
JAMES NATHAN MANTON.
